Attorney

UNITED STATES PATENT OFFICE.

OSCAR KESSLER, OF GREEN ISLAND, NEW YORK.

BURGLAR ALARM.

Application filed December 16, 1920. Serial No. 431,118.

To all whom it may concern:

Be it known that I, OSCAR KESSLER, a citizen of the United States of America, residing at Green Island, in the county of Albany and State of New York, have invented new and useful Improvements in Burglar Alarms, of which the following is a specification.

Reference may be had to the accompanying drawings, and the reference characters marked thereon, which form a part of this specification. Similar characters refer to similar parts in the several figures therein.

The principal object of the invention is to provide a burglar alarm which can be inconspicuously operated by a person standing at a desk or counter, as for example, the counter of a paying teller in a bank.

Other objects will appear in connection with the following description.

The single figure of the drawing is a view in perspective showing my improved alarm mechanism mounted upon the floor and partition wall of a paying teller's booth or cage or the like.

Referring to the drawings wherein the invention is shown in preferred form, 1 is the floor, and 2 is the partition wall of a paying teller's booth or cage, which booth, cage or the like is provided with the usual counter, 3, projecting inwardly from the partition wall.

Beneath the counter, I mount upon the floor, 1, a foot-support, 4, in fixed relation to the floor and preferably upwardly and inwardly inclined to its inner end, 5, whereat it terminates abruptly.

Pivots mounted upon the inner end of the foot-support, 4, by means of a horizontal hinge, 6, is a circuit-breaking plate, 7, which projects above the inner end of the foot-support, 4, in position to be moved by movement of a foot inwardly along the foot-support.

45 A coil-spring, 8, tends to yieldingly force the plate, 7, toward the foot-support, 4.

A shelf, 9, extends from the partition, 2, over the circuit-breaking plate, 7, and foot-support, 4, forming a convenient foot-rest for the attendant at the desk or counter.

Upon the underside of the shelf, 9, is mounted a yielding detent, 10, which may be of any known form adapted to hold the circuit-breaking plate, 7, against the force of the spring, 8, in the foot-induced alarm position of the plate.

I have shown the detent in the simple form of a plate of resilient sheet-metal attached at one end by means of screws, 11, to the underside of the shelf, 9, and having 60 its other end bent to approximately V-form to form a beveled or inclined hook adapted to yield to the foot-induced movement of the plate, 7, and to automatically spring into locking position as soon as the plate has 65 passed the end of the hook.

Electric circuit wires, 12, are connected one to the plate, 7, by means of a contact screw, 13, and the other to a contact plate, 14, mounted upon the foot-support, 4, where- 70 by the circuit in which the wires, 12, are included is maintained closed so long as the plate, 7, is released to the control of the spring, 8.

The operation of the apparatus is as fol- 75 lows:

So long as there is no occasion for alarm, the parts remain in the position shown in the drawing with the plate, 7, held by the spring, 8, adjacent to the inner end of the 80 foot-support, 4, with the contact-screw, 13, in contact with the contact-plate, 14, thus closing the circuit through the wires, 12, which include an electrically actuated sig- 85 nal alarm, not shown, which may be of any known form.

Should there be cause for alarm the attendant at the desk moves or slides his foot inwardly along and over the foot-support, 4, into engagement with the circuit-breaking 90 plate, 7, which readily yields to such movement, thereby separating the contact-screw, 13, from the contact-plate, 14, and breaking the circuit through the wires, 12, thereby causing the alarm signal to be sounded or 95 otherwise given.

Ordinarily it is desirable in case of alarm to have the alarm signal continued indefinitely until intentionally discontinued; and the operator can readily accomplish this by 100 displacing the plate, 7, sufficiently to cause it to be interlocked with the hook of the detent, 10.

As the foot-actuated mechanism is concealed beneath the counter and shelf, 9, the desk-attendant can by an inconspicuous and not unnatural movement of the foot, operate the alarm and cause it to continue operation indefinitely while he may move away from the desk in compliance with the orders of 110 burglars or the like.

The shelf, 9, not only tends to conceal and

protect the plate, 7, and detent, 10, but also serves as a convenient rest upon which the attendant can place his foot without danger of accidentally operating the alarm.

5 I have shown the contacts, 13 and 14, arranged for use in a closed-circuit alarm system, but I do not wish to be limited to such a system as only obvious changes would be necessary to adapt the apparatus for alarm 10 systems of different kinds.

The circuit-breaking plate, 7, can be reset in normal position by forcing the hook of the detent out of engagement with the plate, releasing the plate to the action of the 15 spring, 8. The detent can thus be disengaged by the foot of the attendant or operator. For certain purposes of the invention the foot support may be formed by any floor or member mounted upon a floor 20 in position to accomplish the objects above stated. I prefer however to have the foot

support upwardly and rearwardly inclined as shown so that in making the several operating movements of the foot, the foot is not forced out of natural position or out of natural swinging position as might be the case if it were required to force the foot away from the body along a level floor.

What I claim as new and desire to secure by Letters Patent is—

25 A fixed upwardly and rearwardly inclined foot-support; a yielding circuit-breaking plate pivoted adjacent to, below, and projecting above, the inner end of the foot-support in position to be moved by movement of a foot along said support; a shelf overhanging said plate and foot-support; and an automatic detent beneath said shelf for holding 30 said plate in foot-induced position.

In testimony whereof, I have hereunto set my hand this 7th day of December, 1920.

OSCAR KESSLER.
